[57] CLAIM

The ornamental design for a vertical droplet model, as shown and described.

DESCRIPTION

FIG. 1 is a top plan view of a vertical droplet model showing our new design.

FIG. 2 is a bottom plan view thereof.

FIG. 3 is a left side elevational view;

FIG. 4 is a right side elevational view;

FIG. 5 is a second left side elevational view;

FIG. 6 is a bottom perspective view; and,

FIG. 7 is a top perspective view of FIG. 1.
